UNITED STATES PATENT OFFICE.

CHARLES S. BUSHNELL, OF ROCHESTER, NEW YORK, ASSIGNOR TO GENERAL RAILWAY SIGNAL COMPANY, OF ROCHESTER, NEW YORK, A CORPORATION OF NEW YORK.

AUTOMATIC TRAIN CONTROL.

Application filed June 9, 1920. Serial No. 387,688.

To all whom it may concern:

Be it known that I, CHARLES S. BUSHNELL, citizen of the United States, residing at Rochester, in the county of Monroe and State of New York, have invented certain new and useful Improvements in Automatic Train Controls, of which the following is a specification.

This invention relates to automatic train control systems for railroads, and more particularly to an arrangement of devices and circuits by means of which the necessary controlling impulses or influences may be transmitted from the trackway to moving locomotives, or other railway vehicles, by electromagnetic induction and without mechanical contact.

40 In systems of the type to which this invention is more particularly applicable, a voltage or current is induced in a car carried circuit by suitable trackway means, and this voltage or current is utilized to cause operation of a relay or similar electro-responsive device so as to set into operation some suitable form of train control mechanism, thereby applying the brakes, regulating the speed or otherwise controlling the movement of the vehicle. The purpose of the present invention is to provide an organization of parts and circuits in a system of this type, such that the operation of the relay or similar electro-responsive device, resulting from the voltage or current change in the car carried circuit, will in turn produce a similar voltage or current change, likewise tending to cause operation of the relay, so that the operation of the relay is made more positive and reliable, and of a longer and more uniform duration.

Other detail features and advantages of the invention will appear hereinafter as the description progresses.

In describing the invention in detail reference may be made to the accompanying drawings, in which—

Figure 1 shows diagrammatically one arrangement of trackway circuits which may be employed in connection with the impulse transmitting means embodying this invention; and

Fig. 2 illustrates in a simplified and diagrammatic manner one form of the car equipment and a track element, the parts being shown more with the view of en-

bling it easy to understand the principles of the invention than with the idea of showing the construction and arrangement of parts preferably employed in practice.

In the embodiment of the invention illustrated, the transmission of the desired controlling impulses is produced by track elements which are governed in accordance with traffic conditions. Various arrangements of trackway circuits suitable for this purpose may be employed, and it should be understood that the arrangement shown in Fig. 1 is only typical. Referring to Fig. 1, the track rails 1 of the railroad track are divided by insulated joints 2 into blocks 3 in the usual way, one block I with the adjacent ends of two other blocks H and J being shown. The parts and circuits associated with the various blocks are the same, and for convenience will be given like reference characters, with distinctive exponents. Each of the blocks is provided with a track battery 3 and a track relay 4, the same as in ordinary block signal systems. My invention may be used with or without the usual fixed signals, depending upon the type of train control apparatus; and I have illustrated such fixed signals S conventionally, without attempting to illustrate their well known control circuits and devices.

The trackway element T of my invention in general comprises a magnetic yoke or core and associated coils, and is adapted to influence by electro-magnetic induction a cooperating element on a passing vehicle. In the construction illustrated, the trackway element T comprises a U-shaped core or yoke 5 provided with pole pieces 6, and having coils 7 on its legs which are wound and connected in series so that the electromotive forces generated in these coils by flux passing through the yoke 5 are cumulative or additive. These trackway elements T are intended to transmit controlling influences or impulses to a passing train at one or more control points in each block, in accordance with traffic conditions in the next block in advance alone, or both the next block in advance and the corresponding block, depending upon the type of train control apparatus employed. In the trackway equipment shown in Fig. 1, a trackway element T is located at the entrance to each block, a short distance in

the rear of the insulated joints 2, the normal direction of traffic being from left to right, as indicated by the arrow. The coils 7 of each trackway element T are connected 5 in series in a normally closed circuit including the front contact of a line relay 8. In the arrangement illustrated, the controlling circuit for the line relay 8 includes a front contact of the track relay 4 of the corresponding 10 block and a front contact of the track relay 4 of the next block in advance, so that the coils 7 of the trackway element T at the entrance to each block are in closed circuit under clear traffic conditions, but 15 are open-circuited when either the corresponding block or the next block in advance is occupied. The trackway elements T may be located crosswise of the track between the track rails (as shown in Fig. 1), or 20 lengthwise, or outside of either track rail, as preferred.

The car carried element L for cooperating with the trackway elements T comprises a yoke or core 9 having three legs each provided with a pole piece 10. This yoke 9 is supported in any suitable way from the frame of the locomotive, or other vehicle, and is positioned so that two of its legs, which are spaced apart the same distance 25 as the legs of the track element T, will pass directly over the pole pieces of said track element, as shown in Fig. 2. On one of the legs of the yoke 9, (the middle leg in the particular arrangement illustrated) is a coil 30 or winding 11, conveniently termed the primary coil; and on the other two legs are similar coils 12 and 13, conveniently termed secondary coils. The secondary coils 12 and 13 are wound, preferably with the same 35 number of turns, and connected in series so that electro-motive forces generated therein by flux passing through the legs of the yoke L in the same direction, either up or down, will oppose each other.

40 In connection with the system illustrated, there is employed a device of the thermionic or vacuum bulb type, commonly known as audion and conveniently referred to by that term. This audion, being well known in the art, is illustrated conventionally. It 45 comprises a filament F, a grid G, and a plate P. This audion is connected up with suitable sources of current illustrated as batteries A, B and C, the primary and secondary coils of the car carried element L, and a control relay R, so that the operation of said relay R is automatically determined by the controlling condition of the track elements T as the vehicle successively passes 50 them. It should be understood that these electrical connections may take various forms, the arrangement illustrated being merely typical.

The control relay R may be of any suitable type, but I prefer to employ a relay of

a tractive type having its armature balanced about its center of gravity and biased to open by a spring; and in connection with the arrangement of circuits illustrated, I have found it desirable to use a relay having 70 a large number of turns so as to be operable on small currents, and also having a laminated core so as to be quick acting. It will be evident, however, that the structural features of the relay R depend largely upon the 75 type of audion employed, and other characteristics of the system. The control relay R is intended to control the operation of some suitable form of train control apparatus. Since this apparatus forms no part 80 of the present invention, and may take any one of the various forms known in the art, I have illustrated conventionally such a device K in the form of an electro-pneumatic valve, which may be used to vent the train 85 pipe and apply the brakes directly, or govern the operation of some other form of speed regulating or brake controlling mechanism. This train control device K is normally energized, and deenergized when 90 the control relay R opens its contacts. In the arrangement of circuits illustrated, the control relay opens its contacts only momentarily, so that if continued operation of the train control device K is desired, some 95 suitable means, such as a stick circuit, should be employed, all in the manner which will be readily understood by those skilled in the art.

The apparatus so far described constitutes 100 the parts of a system which I have selected to illustrate the principles and mode of operation of my improvement. In accordance with the present invention, I employ a transformer or induction coil, or equivalent device, for inductively coupling the car carried circuit influenced from the trackway, and the circuit controlled by the relay R. This transformer O is shown diagrammatically, and comprises two coils or windings 105 110 and 15.

The circuit connections between the various devices described will, of course, vary in practice. In the particular arrangement illustrated, the filament F of the audion is 115 heated by the battery A. The grid G is connected in circuit with the secondary coils 12 and 13 and the battery C, as follows: commencing at the positive terminal of the battery C, wire 16, winding 15 of the transformer O, wire 17 and the secondary coil 12, wire 18, secondary coil 13 and wire 19 to the grid G, filament F and back to the other terminal of the battery C. The plate P is connected in circuit with the relay R and the 120 batteries B and C, as follows: commencing with positive terminal of the battery B, wires 20 and 21, relay R, wire 22, to the plate P, filament F to the other terminal of the battery C. The primary coil 11 is normally 125 130

energized by a circuit as follows: commencing with positive terminal of the battery B, wires 20 and 23, train control device K, wire 24, contact finger 25 and front contact 5 of control relay R, wires 26 and 27, winding 14 of transformer O, wire 28, primary coil 11, wire 29, adjustable resistance 30 and wire 31 to battery C, thence to battery B. In order to protect the relay contacts from injury by the arcs accompanying the interruption of this inductive circuit, a resistance 32 is preferably connected in multiple with the relay contacts.

Operation.—Normally the battery C produces a positive potential upon the grid G with respect to the negative end or average potential of the filament F, and thus permits current to flow in the plate circuit through the relay R, on account of the well known characteristic of the audion. The relay R being energized, current flows through the primary coil 11 and produces magneto-motive force tending to send flux through the yoke 9. When the car is traveling between track elements T, this flux passes in part through the legs of the yoke 9 and in part through leakage paths. The reluctance of the partial magnetic circuit afforded by the yoke 9 is relatively high. Assume now that the car passes over a track element T which has its coils 7 open-circuited, corresponding to dangerous traffic conditions ahead. A track element T in this condition presents in effect a dead magnetic loop for the two lefthand legs of the yoke 9 on the passing car, and it will be evident that as the car passes such magnetic loop, the reluctance of the partial magnetic circuit of the yoke 9 through the primary 30 coil 11 and the secondary coil 12 is greatly changed, being decreased from the normal to a minimum and then back to normal as the car passes the track element. This change in reluctance in turn changes the amount of flux passing through the coils 11-12, the flux normally passing through the leakage paths being diverted to the path of lower reluctance through the iron of the yokes 9 and 5. As the flux through the coil 50 12 is increased, an electro-motive force is induced in said coil, which in accordance with well known laws, tends to oppose the current setting up this flux; and the windings are so arranged that this induced electro-motive force opposes the voltage of the battery C and reduces the potential on the grid G. The normal potential on the grid G being thus lowered, the current normally flowing in the plate circuit through the control relay R is likewise decreased, and the parts are so proportioned and adjusted that the current through the relay R is reduced in this way below the value of current required to hold its contacts closed. Consequently, the contacts of the relay R open

and deenergize the train control device K. As the car again recedes from the track element the flux through the secondary coil 12 again decreases, but since the train control device has already been actuated the effect 70 of this decrease of flux need not be considered. Under clear traffic conditions, the coils 7 of the track element T are included in a closed circuit of low resistance; and when the car carried element L passes over 75 a track element in this clear condition, the car equipment is not influenced, at least sufficiently to cause operation of the relay R. This is attributed to the action of the coils 80 7 which, it is believed, oppose or choke back the passage of flux through the yoke 5 because of the current induced in said coils. It is found in practice that the number of turns on the coils 7, the length of the magnetic circuits, and the like, may be proportioned so that there is little change in the flux through the secondary coil 12 as it passes the track element T having its coils in closed circuit.

It will be evident that track rails or similar masses of iron along the track will tend to cause operation of the control relay R in the same way as a track element T in the danger or stopping condition; and to neutralize this objectionable interference, more 90 particularly in the case of track rails, the additional leg and secondary coil 13 are employed. If both of the outer legs of the yoke 9 pass over a magnetic body, as a track rail, substantially the same change in flux 100 takes place through the coils 12 and 13; and since these coils are wound oppositely, the electro-motive forces induced therein are approximately balanced, so that the potential of the grid G is not lowered. This feature 105 of the system, whereby it is protected against improper operation by the interference of rails or similar masses of iron along the track, forms no part of the present invention, and merely illustrates the adaptability of this invention.

The above explanation outlines briefly my understanding of the way in which the car carried and track elements shown and described cooperate, and act in conjunction 115 with the audion, to cause operation of the control relay R when required under dangerous traffic conditions, and when not required under clear traffic conditions; but other factors not necessary to consider are involved to some extent in the operation. This system is disclosed and claimed in other applications.

The transformer or induction coil O inductively connecting the grid circuit through the secondary coils 12 and 13, and the control circuit through the device K, contacts of relay R, and the primary coil 11, acts to cause more positive operation of the relay R and prolong the opening of its contacts. When 125 130

the car passes over a track element in the danger or stopping condition, and the contacts of the relay R open, in the manner already described, the current through the 5 winding 14 of the transformer O is greatly reduced on account of the inclusion of the resistance 32 in the circuit. It is noted here that this resistance 32 is optional and may be omitted or replaced by any other means 10 acting to protect the relay contacts. The reduction of current in the winding 14, occurring when the contacts of the relay R open, acts to induce a voltage in the winding 15; and these windings 14 and 15 are arranged with respect to the potential of the currents flowing in their respective circuits 15 so that this induced voltage, due to the reduction of current in the winding 14, opposes the battery C and causes a further or continuing decrease in the grid potential, thereby further tending to deenergize the relay R. It is found in practice that the slightest opening of the relay R causes it to open fully and to stay open for a short time, that 20 is, for 3 seconds, or more, depending upon the proportion and arrangement of the windings, the normal voltages and the like. Thus, while the reduction in grid potential occasioned by the influence of the track element 25 may be of very short duration, perhaps only sufficient to partly open the contacts of the relay R, the transformer O acts to increase and prolong the opening of said contacts.

30 While I have disclosed my invention in connection with a specific type of system employing an audion, the invention in its generic aspect contemplates the incorporation of suitable means with a car carried circuit having voltage or current changes induced therein inductively by trackway means, and a control circuit responding to such voltage or current changes, such that the current variations in the control circuit resulting 35 from the influence of the trackway means upon the car carried circuit will in turn produce the same effect upon the car carried circuit. In short, when the current in the control circuit energizing the relay R is reduced, this in turn acts upon the circuit through the secondary coils 12 to produce in this latter circuit the same effect as the influence of a stopping track element.

I desire to have it understood that the 40 specific embodiment of the invention shown and described is merely illustrative, and does not exhaust the adaptations and modifications of the idea of means and the functions thereof constituting the invention.

45 What I claim as new and desire to secure by Letters Patent of the United States is:—

1. In an automatic train control system of the type in which variations of potential are produced in a car carried circuit by electromagnetic induction, the combination 50

with said car carried circuit, of a brake applying means, a normally energized electro-responsive means controlled by said circuit, and operating said brake applying means to apply the brakes of the train when actuated, 70 and means responding to the operation of said electro-responsive means for producing like variations of potential in said car carried circuit.

2. In an automatic train control system of the type specified in claim 1, the combination with the car carried circuit, of a normally energized relay controlled by said circuit and deenergized when the potential of said circuit decreases, another circuit controlled by said relay, and means responding to a decrease of current in said another circuit for decreasing the potential in the car carried circuit.

3. In an automatic train control system of the type specified in claim 1, the combination with the car carried circuit, of a relay deenergized when the potential of said car carried circuit decreases, a control circuit including a front contact of the relay, and means inductively connecting the car carried circuit and the control circuit and arranged to reduce the potential of the car carried circuit when the current in the control circuit decreases.

4. In an automatic train control system of the type in which the car carried circuit is influenced temporarily from the trackway by electromagnetic induction under dangerous traffic conditions, the combination with said circuit, of a relay controlled thereby, a normally closed control circuit including the front contact of said relay, a resistance in multiple with said front contact, and means inductively connecting said control circuit and said car carried circuit.

5. In an automatic train control system of the type in which controlling impulses are transmitted from the trackway to moving vehicles by electromagnetic induction and in which the car carried circuit has a counter electro-motive force induced therein under dangerous traffic conditions, a normally energized control circuit having the current therein reduced by the counter electro-motive force in said car carried circuit, and means whereby such reduction of current in the control circuit acts automatically to produce a similar counter electro-motive force in the car carried circuit.

6. In an automatic train control system, a car carried coil, a circuit and a source of current including said coil, means partly on the track and partly on the car for inducing voltage in said coil opposing that of said source, electro-responsive means operated by the decrease in voltage in said circuit, and means controlled by the electro-responsive means for also producing voltage in said circuit opposing said source.

7. In an automatic train control system, car equipment comprising a magnetic core, a normally energized primary coil and a secondary coil on said core, trackway means for varying the reluctance of the magnetic circuit through said core, an audion having its grid connected to said secondary coil, a relay included in the plate circuit of the audion, and means controlled by said relay 10 for producing a change in the potential of said grid.
8. Car equipment for automatic train control systems comprising a coil and a core therefor adapted to be influenced by electro-15 magnetic induction from the trackway, an audion, a circuit including the coil and connected to the grid of the audion, a relay in the plate circuit of the audion, a control circuit including the front contact of the 20 relay, and means inductively connecting the control circuit and the first mentioned circuit through the coil, whereby operation of the relay also changes the grid potential and tends to cause further operation of said 25 relay.
9. Car equipment for automatic train control systems comprising a circuit adapted to be influenced by electro-magnetic induction from the trackway, an audion having its grid potential controlled by said circuit, 30 a relay in the plate circuit of the audion, a normally energized train control device, a control circuit including said device and a front contact of the relay, and means inductively connecting the first mentioned circuit and the control circuit.
10. Car equipment for automatic train control systems comprising a magnetic yoke, an primary and secondary coils on the yoke, an 40 audion having its grid connected to the secondary coil, a relay in the plate circuit of the audion, a train control device, a control circuit including said device, a front contact of the relay and the primary coil, 45 and a transformer having its windings included in the control circuit and the grid circuit.
11. Car equipment for automatic train control systems comprising a magnetic yoke having three legs, a normally energized primary coil on one leg, oppositely wound secondary coils on the other legs, an audion having its grid connected to the secondary coils in series, a relay controlled by the plate 50 circuit of the audion, a normally closed control circuit governed by the relay, and a transformer having its windings included in the grid circuit and control circuit.
12. Car equipment for automatic train control systems comprising a magnetic yoke having three legs, a primary coil on one leg, oppositely wound secondary coils on the other legs, an audion having its grid circuit connected to the secondary coils in series, a 55 relay in the plate circuit of the audion, a normally energized train control device, and a transformer inductively connecting the grid circuit and the control circuit.
13. In an automatic train control system of the type in which variations in potential are produced in a car-carried circuit, the 60 combination with said circuit, of a normally energized electro-responsive device influenced in accordance with such potential changes in said circuit, and automatic means for temporarily extending the time of operation of said device.
14. In an automatic train control system of the type in which variations in potential are produced in a car-carried circuit, the 65 combination with said circuit, of a relay energized and deenergized in accordance with potential changes in said circuit, and automatic means effective upon opening of the contacts of the relay for causing the re-energization of the relay to lag behind the 70 corresponding potential change in said circuit and thereby extend the time of opening of the relay.
15. In a train control system, a relay on a vehicle, means partly on the vehicle and 75 partly on the track for temporarily reducing the current in said relay, and automatic means having limited time of effective action and acting upon opening of the relay contacts to extend the time of such reduction in current through the relay and thereby increase the time during which its contacts are opened.
16. In a train control system, a normally energized car-carried circuit, an electro-80 responsive device in said circuit, means partly on the car and partly on the track for governing said circuit to temporarily reduce the current through the relay and cause its contacts to open, and automatic 85 means rendered effective by the opening of the relay contacts for governing said means to maintain the contacts open for an interval of time after the trackway control ceases.
17. A train control system comprising a 90 car-carried circuit including a battery, an electro-responsive device on the car governed by said circuit, means partly on the track and partly on the vehicle for producing in said circuit at times a voltage opposing the battery and thereby cause operation of the electro-responsive device, and automatic 95 means acting automatically upon the operation of the electro-responsive device to temporarily produce additional voltage changes in said circuit and thereby extend the time of operation of the electro-responsive device.
18. In a train control system, train control apparatus on a vehicle, electro-responsive means on the vehicle for governing the 100

- operation of said apparatus, means including track elements and a cooperating car-carried element acting by transfer of magnetic flux to cause operation of said electro-responsive means by reducing the flow of current therein, and automatic means for temporarily extending the time of operation of said electro-responsive means by acting on said electro-responsive means in the same manner as does said last mentioned means.
19. Car apparatus for train control systems comprising a constantly acting source of magneto-motive-force, a partial magnetic circuit including said source, an electro-responsive device, a governing circuit for said device inductively associated with said circuit, and separate automatic means responsive to the operation of said device for temporarily producing a potential change in the governing circuit and thereby extend the time of operation of said device.
20. Car equipment comprising a magnetic core, a primary coil and a secondary coil inductively associated with said core, an energizing circuit for the primary coil, an electro-responsive device, a governing circuit for said device including the secondary coil, and means inductively connecting said circuits.
21. Car apparatus for train control systems comprising, an electro-responsive device, a car-carried circuit for normally energizing said device, means influenced from the trackway through an intervening air gap for changing the current flow in said circuit to cause operation of said device, a circuit opened by operation of said device, and other car-carried means continually inductively connecting said circuits.
22. Car apparatus for train control systems comprising, an electro-responsive device and a governing circuit therefor, means influenced from the trackway, and acting upon an increase of flux to induce a voltage in said circuit and cause operation of said device, and other automatic means acting by induction between closed circuits for influencing said governing circuit and thereby temporarily prolonging the time of operation of said device.
23. Car apparatus for train control systems comprising, an electro-responsive device, a normally energized governing circuit therefor acting to cause operation thereof upon a predetermined change in potential, a transformer acting upon decrease of current in its primary to cause such predetermined change in potential in the governing circuit, and means for varying the current in the primary of said transformer upon operation of the electro-responsive device.
24. In a train control system, a normally energized car-carried circuit, an electro-responsive device governed thereby, means partly on the car and partly on the track for producing potential changes in said circuit by the transfer of magnetic flux and automatic means effective when the electro-responsive device is operated for temporarily producing like potential changes in said circuit and thereby temporarily prolong the time of operation of said device.
25. Car apparatus for train control systems comprising, a normally energized relay, cooperating track and car-carried elements acting by the transfer of magnetic flux to reduce the current through the relay and thereby cause opening of its contacts, and automatic means rendered effective by the opening of the relay contacts for continuing the reduction of current through the relay for a limited time.
26. Car apparatus for train control systems, comprising an electro-responsive device, a car-carried circuit, means inductively influenced from the trackway through an intervening air gap for changing the current flow in said circuit and causing operation of said device, and automatic means rendered effective when said device operates for in turn governing the car-carried circuit to prolong temporarily the time of operation of said device.
27. Car apparatus for train control systems comprising, a car element having a primary winding and a secondary winding, a primary circuit, a normally energized brake control device, in series with said primary winding in said primary circuit, a relay governed by said secondary winding, and means including the contacts of said relay and acting by induction to control the flow of current in said secondary winding without interrupting said primary circuit.
28. Car apparatus for train control systems comprising, a normally energized electro-responsive device of the tractive armature type, a car-carried circuit influenced from the trackway for causing operation of said device, a circuit governed by said device, and means inductively connecting said circuits.
29. Car apparatus for train control systems comprising, a car element adapted to inductively communicate with suitable apparatus along the trackway and having a primary and a secondary winding thereon, two circuits each including one of said windings, and an alternating current transformer for inductively coupling said circuits.
30. Car apparatus for train control systems comprising, a three-legged core of magnetic material, a primary coil on one of said legs, oppositely wound and connected secondary coils on the other legs, a circuit including said primary coil, a circuit including said secondary coils, and separate means for inductively coupling said circuits.
31. Car apparatus for train control systems comprising, two coils adapted to in-

ductively communicate with suitable apparatus along the trackway, a circuit for each of said coils, an audion associated with one of said circuits, and separate means for 5 inductively coupling said circuits.

32. Car equipment comprising, a car element consisting of a core of magnetic material located on the car to magnetically communicate with an inductive trackway device, 10 a primary and a secondary coil inductively associated with said core, an energizing cir-

cuit for the primary coil, an electro-responsive device, a governing circuit for said device including said secondary coil, and means for inducing a current in said governing 15 circuit to actuate said electro-responsive device when the current in said energizing circuit decreases.

In testimony whereof I have affixed my signature.

CHARLES S. BUSHNELL.
